MOLDING MACHINE

Allen Kissam, Orlando, Fla.

Application October 29, 1937, Serial No. 171,771

12 Claims.

(Cl. 25—41)

This invention relates to machines for making hollow molded articles, more particularly concrete blocks of the type used in building construction.

5 A primary object of the invention is to provide a mold structure which adequately and thoroughly tamps the semi-wet mixture of concrete in a rapid and efficient manner thereby materially speeding up production while at the same time providing a strong and durable product. 10 In that connection the distinctive feature of the invention resides in the use of a mold core which is primarily intended to move with short strokes at a relatively high frequency in the direction of the walls of the mold box or the material forming block, thereby quickly and effectively to tamp the mixture in the mold.

Another object of the invention is to provide novel means for mounting and actuating the 20 mold core.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which:

30 Figure 1 is a front elevation of the apparatus embodying the present improvements.

Figure 2 is a side elevation.

Figure 3 is a vertical sectional view taken on the line 3—3 of Figure 1.

35 Figure 4 is a vertical sectional view taken on the line 4—4 of Figure 3.

Figure 5 is a detail perspective view of the vibrating core unit.

Figure 6 is a detail view of the eccentric and 40 link means for operating the vibrating core, the same being taken on the line 6—6 of Figure 3.

According to the embodiment of the invention shown in the drawings the same includes in its organization a mold box 1 supported by a 45 suitable framework 2. The mold box may be of any desired size or dimensions according to the specification of the block to be made, but for purposes of illustration the apparatus shown is intended to make a single block with two 50 air cells.

Shiftably mounted above the mold box 1 is a hopper 3 for receiving the semi-wet concrete of which the block is to be formed. The hopper 3 is slidably mounted in guides 4 for horizontal movement so that it may be shifted manually

back and forth over the mold box 1 alternately to guide the concrete charge into the box, and, after the block has been completed, remove the excess concrete and trowel the upper edges of the block. It will, of course, be understood that the bottom of the hopper is open, and that a suitable plate or apron 5 is mounted between the guides 4 to retain any material remaining in the hopper 3 prior to the latter being shifted back over the mold box.

10 Within the mold box 1 there is provided an ejecting or block lifting frame designated generally as 6, the same being mounted at its ends upon vertical standards 7 slidably guided in the opposite legs of the frame. The lower ends of the standards are connected by a strap or cross-bar 7a, and also have arranged therebetween a roller 8. This roller is adapted to be engaged by the arms 9 of an ejecting lever designated generally as L, and which is pivotally mounted in the framework of the machine as indicated at 10. Said lever L is preferably provided near its outer end with a counterweight 11 for holding the arms 9 in their elevated position when the completed block is to be removed from the machine.

15 The charge of concrete from which the block is made rests upon a pallet 12 which is loosely mounted on and carried by the frame 6. This pallet is preferably of triangular cross-section 20 with one of its sides horizontal and although it snugly fits into the mold box, and within and about the cores 13, nevertheless, there is sufficient clearance to permit motion of the core. And, moreover, the clearance provided by the 25 shape of the pallet prevents concrete from packing between itself and the side of the mold box.

The core or cores 13 are mounted centrally within the mold box and within the openings of the pallet and ejector frame and preferably have their upper ends 14 extending to the top of the mold box while their lower ends 15 terminate below the bottom edge of the ejector frame 6. Each core 13 is mounted on the enlarged supporting end 16a of a lever arm 16 40 carried by a supporting shaft 17 so that it may have a relatively pivotal movement about the shaft and will be capable of oscillating or rocking motion whose greatest amplitude of movement is, of course, at the upper end 14 of the 45 core. The free end 18 of each lever arm is pivotally connected by a bifurcated lug 18a to a link 19 by the pivot bolt 20 or its equivalent. The upper end of the link 19 is formed with an opening and is mounted on an eccentric cam 21 car- 50

55

- ried by a cam shaft 22. This shaft is common to all of the eccentrics for the core operating arms and is provided at one end with a suitable driving connection 23 in the form of a pulley, or gear as the case may be, which receives power from any suitable source, such as an electric motor M. This motor may be mounted on a bracket or shelf 24 beneath the plate or apron 5 underlying the hopper.
- 10 The eccentrics 21 on the shaft 22 for the several arms connected with the cores preferably have an angular relationship of 180° so that adjacent core members are rocked or oscillated in opposite directions. Thus, when power is applied to the shaft 22 it will be apparent that the eccentrics 21 will cause the links 19 to rise and fall and thus oscillate the arms 16 connected with the cores, thereby imparting to the latter a rocking movement.
- 15 20 In practice it is customary to rotate or drive the cam shaft 22 carrying the eccentrics 21 at relatively high speed, that is, in the neighborhood of 1800 revolutions per minute, thereby to impart a very rapid rocking movement to the cores. The leverage between the shaft 17 which supports the core arms or levers and the pivots 20 which connect the links 19 with the eccentrics 21 is such that the upper ends 14 of the cores have only relatively slight rocking movement,
- 25 30 for example, in the neighborhood of $\frac{1}{8}$ ". Therefore, it will be apparent that the cores 13 are given a rapid oscillating or rocking movement under the power supplied from the shaft 22.
- 35 40 In using the machine, the charge of semi-wet concrete is placed in the hopper 3 while it is located over the mold box and the cores 13 are vibrating. As the material forming the charge passes into the mold box it will be tamped or packed progressively from the pallet 12 upwardly, thus producing very dense front and rear walls in the block in a comparatively short space of time, for example, approximately twelve seconds. The effect of the rocking or oscillating core 13 is to drive the air out of the charge of concrete very quickly and at the same time pack the same laterally and downwardly toward the front and rear of the block. While the material between the cores is not compressed to the same degree as the material at the front and rear of the block, nevertheless it becomes very rapidly settled, packed, or jarred in the space between the cores due to the fact that adjacent cores are oscillating at all times in opposite directions, to provide a strong bond between the front and rear portions 45 50 of the block. It will, of course, be understood that the material forming the end walls of the block, that is, between the outer faces of each core and the ends of the mold box will also be tamped or settled by the vibrating movement of the cores 13 so that the density of the end walls of the block is comparable with that of the intermediate walls or webs formed between the cores.
- 55 60 When the block has been finished the hopper 3 must be moved rearwardly on the guides 4 to clear the mold box and trowel or smooth the upper edges of the block, and, at the same time remove excess material onto the apron 5. The block is then ready for ejection from the machine through the manipulation of the lever L. As the operator moves the weighted handle portion of the lever L and causes the same to rock on the pivots 10 the arms 9 engage the roller 8 carried by the standards 7 causing the latter to move upwardly and push the finished block toward

the top of the machine. The arms 9 are limited in their outward movement by the strap 9a. The weight 11 on the lever L is sufficient to balance the weight of the frame 6, pallet 12, and the completed block while the lever is in its forward position thereby to hold the same against the limiting strap 9a.

6 10 In connection with the cores 13, it may be pointed out that the same are preferably bolted to the enlarged portion 16a of the lever arm 16 by the bolts 13a so that the cores may be readily removed and replaced when desired.

15 20 From the foregoing it will be apparent that the present invention involves as its distinctive feature the provision of a core which vibrates in the direction of a vertical wall of the block as it is being formed, preferably at relatively high frequency, to thoroughly and adequately tamp the material of which the block is made in a most expeditious and satisfactory manner.

25 30 The material of the block is progressively tamped from the bottom of the cores against the sides of the mold and toward the top, and the amplitude of movement of the rocking core not only has the effect of packing or tamping 25 the material downwardly on each oscillation, but, because of its rapid vibration quickly distributes the charge throughout the mold box so that a strong and dense block is formed.

35 40 While the construction illustrated herein, by way of example, proposes to mount the core to rock or oscillate in producing the vibratory motion, nevertheless, it will be understood that equivalent means for producing the desired movement are within the scope of the invention. For example, the core may be slidably mounted and the shaft 17 may be power driven and eccentrics, equivalent to the eccentrics 21, may be mounted thereon to operate in suitable openings 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

51 I claim:

52 1. A concrete block making machine including a mold box, a plurality of cores in said box, means for pivotally supporting said cores at their lower ends, lever means extending from said last named means and below said point of pivotal support for the cores, and power driven eccentric cams connected with said lever means, said cams having an angular relation of 180° to impart oscillating motion in opposite directions to the cores.

53 2. A concrete block making machine, including a frame, a mold box carried by the frame, an ejector frame mounted for vertical movement within the mold box, a pallet resting on the ejector frame, a core extending upwardly through the ejector frame and pallet to approximately the top of the mold box, said core also projecting below the ejector frame, mounting means for the core including a pivot shaft, a lever arm carried by said mounting means below said pivot shaft and extending laterally from the frame of the machine, power driven eccentric means connected to the free end of said arm and weighted angular lever means for operating the ejector frame.

54 3. A concrete block making machine including,

in combination, a mold box including stationary walls, stripper means adapted for vertical operation within the mold box, a pallet resting on the stripper means, a core permanently maintained in fixed relation to the bottom of the mold box and extending through the stripper means and pallet, said core also projecting below the stripper means, and means for actuating said core on its pivotal mounting to impart an angular movement said core relative to the walls of the mold box.

4. A concrete block making machine including, in combination, a mold box including stationary side walls, vertically movable stripper means normally positioned in the lower part of the mold box, a core having its upper end substantially flush with the upper end of the mold box and having its lower end projecting through said stripper means, a mounting for the core including a fixed horizontal pivot adjacent and below the stripper means, a lever arm extending from said pivotal mounting, and means for operating said lever to impart movement to the core relative to the walls of the mold box.

5. A machine for making concrete blocks, including, in combination, a frame, a mold box including stationary walls carried by the frame, a stripper mounted for vertical movement in the mold box, a rectangular core permanently positioned in and vertically disposed throughout the depth of the mold box and having walls substantially parallel with the walls of the box, a shaft having a fixed position in the frame on which the core is mounted, and means for imparting angular movement to the core about the shaft whereby the walls of the core tamp the mixture to be molded against the walls of the box throughout their vertical depth.

6. A machine for making concrete blocks comprising, in combination, a mold box including stationary walls, vertically movable stripper means normally positioned in the lower part of the box, a vertically disposed core permanently positioned within the mold box, means adjacent and below the lower end of the core mounting the same for angular movement relative to the walls of the box and means for imparting rapid movement to the core.

7. A machine for making concrete blocks comprising, in combination, a mold box including stationary walls assembled in box formation, a stripper device mounted for vertical movement in the mold box and normally disposed at the lower end of the box, a vertical core permanently positioned within the mold box, means adjacent and below the stripper device for pivotally supporting the lower end of the core, and means for imparting vibrating movement to said core through said last named means.

8. A concrete block making machine including in combination, a stationary mold box open at top and bottom, vertical stripper means, positioned normally in lower part of mold box, a pallet placed on said stripper means, cores extending upwardly through said pallet to the top of mold box and pivotally mounted permanently within said mold box; said core mounting being 5 permanently positioned near that point on the core which is surrounded by the pallet, lever arms attached to lower part of the cores and extending laterally outwards, power driven means, means connecting said power driven means to 10 said lever arms whereby the latter impart rapid vibratory movement to the cores, and a hopper on top of said mold box and free to be moved so as to clear said mold box and permit block to be stripped therefrom; said hopper when positioned over the mold box serving to guide material into said mold box and at the same time to hold an excess of concrete whose weight assists in packing material in mold box while the cores are rapidly vibrating therein.

9. A concrete block making machine consisting of a vertical stationary mold-box open at upper and lower ends in combination with a plurality of vertical cores mounted permanently within said mold box on horizontal bearings placed near lower ends of cores, lever arms attached to the lower ends of cores, link and eccentric means including a shaft, said means giving the cores a definite rocking motion at a definite speed, a pallet, and vertical stripping means operating in 20 conjunction with the pallet.

10. A concrete block making machine consisting of a stationary vertical mold box, in combination with a plurality of cores in said box, means for pivotally supporting said cores near 35 their lower ends, lever means extending from said last named means, and power driven eccentric means connecting with said lever means to impart rocking motion to the cores, and vertical stripping means in said box.

11. A concrete block making machine consisting of a stationary vertical mold box in combination with a plurality of cores surrounded at their lower ends by a pallet, said cores being so mounted that they can rock and tamp or pack 45 the concrete between themselves and the walls of the mold box while being surrounded by said pallet, the rocking motion of the cores being at such a speed that the concrete is vibrated while being packed, and vertical stripper means for 50 the pallet.

12. A machine for making concrete blocks comprising in combination, a mold box including stationary walls assembled in box formation, a stripper device operating within the mold box, a movable core vertically positioned within the mold box and presenting flat side portions, means for supporting the said vertical core to permit relative motion between its said walls and the mold walls, a lever connected with the core, and means 55 for imparting vibrating movement to said lever.

ALLEN KISSAM.
